UNITED STATES PATENT OFFICE.

STANLEY C. C. CURRIE, OF PHILADELPHIA, PENNSYLVANIA, ASSIGNOR TO THE UNITED ELECTRIC IMPROVEMENT COMPANY, OF GLOUCESTER, NEW JERSEY.

CUT-OUT.

SPECIFICATION forming part of Letters Patent No. 406,268, dated July 2, 1889.

Application filed April 19, 1889. Serial No. 307,755. (No model.)

To all whom it may concern:

Be it known that I, STANLEY CHARLES CUTHBERT CURRIE, a subject of the Queen of Great Britain, but now residing at the city of Philadelphia, in the county of Philadelphia and State of Pennsylvania, have invented a certain new and Improved Automatic Electric Cut-Out, of which the following is a specification.

10 The principal object of my invention is to provide a simple, durable, and sensitive automatic electric cut-out for various uses and purposes possessing the following characteristic features and desirable qualities: first, a 15 device of good conducting material to afford a continuous path for the passage of a current of electricity; second, a device constructed and arranged so that when the electric current becomes more intense than the 20 device is adjusted to carry causing the circuit through the same to be automatically broken, and, third, to provide a device that can be readily readjusted as soon as any defect in the circuit has been rectified.

25 My invention consists of two wires or pieces of metal or other good conducting material interposed in an electric circuit and suitably supported at one of their ends by a connecting device and with portions of the wires or 30 pieces embedded in an insulating substance or material of poor electrical conductivity, but susceptible of being melted at a low temperature, with portions of said wires or pieces immersed in a conducting-fluid contained in 35 a bulb, tube, or other suitable vessel.

My invention further consists of two inversely-disposed wires or pieces of metal or material of good conductivity supported at one of their ends by a connecting device composed of insulating material and portions 40 thereof attached to or otherwise held by an insulated yoke, and said wires or pieces embedded in a substance or material of high resistance, but capable of being readily melted, 45 and with portions thereof immersed in a conducting-fluid contained in a vessel, bulb, or other container, with a loop or band of insulating material circumscribing the vessel or bulb to permit the same to fall sufficiently 50 when the circuit is automatically broken

through the device by the melting of the substance or material of poor electrical conductivity that said wires are embedded in and supported in the vessel.

The nature and characteristic features of 55 my invention will be more fully understood taken in connection with the accompanying drawings, forming part hereof, and in which—

Figure 1 is a vertical central section of the automatic cut-out device embodying the principal characteristic features of my invention; 60 and Fig. 2 is a plan view thereof, showing the wires which lead to or from a source of electricity.

Referring to the drawings for a further description of my invention, A is a block of wood, ebonite, or other preferred insulating material, which constitutes the frame of the device. The inversely-disposed wires or pieces B and B' are supported in or by said 70 frame, which is provided with binding-screws C and C'. The lower extremities of said wires are immersed in a fluid composed of mercury or other preferred liquid D, of high electrical conductivity, contained in a bulb, 75 tube, or other vessel E, made of glass or other preferred insulating material. Portions of the wires B and B' are embedded in the tube, bulb, or other vessel E, in paraffine-wax or other preferred poor conducting material, but 80 such as is susceptible of being melted at a lower temperature than will melt the wires or pieces of metal of good conducting material B and B'. The yoke G, composed of ebonite or other preferred insulating material, 85 consists of a stretcher g, which is provided with side grooves h and h'. The wires B and B', engaging in the grooves h and h' of the yoke G, are held to place by means of a band of insulating material H. A band, of rubber or 90 other preferred material I, is caused to circumscribe the tube, bulb, or other containing-vessel E.

The action of the above-described cut-out device depends upon the heating of the wires 95 by the passage of an electric current larger than they are intended to carry to a temperature capable of melting the insulating material in which they are embedded or retained in position, thereby effecting a change in the 100

arrangement of the parts of the cut-out device to cause the circuit to be broken.

The mode of operation of my improved cut-out device may be explained as follows: The 5 wire constituting a circuit from a source of electricity is cut and the cut-out device interposed in the circuit by attaching the ends of the wires or pieces to the respective binding-screws C and C' of the connecting device A, 10 to the terminals of which are attached wires B and B'. The electric current passes through the binding-screw C and the wire B to the liquid D, contained in the tube or bulb E, and thence through said liquid D, the wire B', and 15 the binding-screw C' to the wire forming the circuit. In the event of the current passing through the circuit being more intense than the cut-out device is capable of withstanding, the wires B and B' will become heated, and 20 the paraffine-wax or other material F is melted in the bulb or tube sufficiently to cause the bulb and the mercury contained therein to fall by their own weight, thereby breaking the circuit. The bulb or tube E is prevented 25 from falling farther than is necessary to always insure the wires B and B' being withdrawn from the conducting-liquid, by the band I surrounding the same.

It will be readily understood in the operation 30 of my improved device that when the wire or piece of metal becomes heated up by the electric current sufficiently to cause the paraffine-wax or other similar material to melt the tube will fall, whereby the contact of the 35 wires with the mercury or other suitable material or substance will be destroyed, and consequently the electric circuit broken; but, however, in the fall of the tube the same is checked by the insulated loop or band I coming 40 in contact with the yoke G. The quantity of current in the circuit necessary to heat the wire or piece B or B' sufficiently to melt the wax and destroy contact, and consequently to cause the tube to fall and the circuit 45 to be broken, may be predetermined by either increasing or diminishing the relative size of the wires or pieces B and B' and the size of the wire forming the circuit. It may be remarked that the paraffine-wax or other 50 preferred insulating material susceptible of being melted at a lower temperature than would melt the wires not only performs the functions hereinabove described, but also protects the conducting-liquid from being exposed to the atmosphere.

The instrument may be adjusted either by pressing the tube upward, so that the wires

B and B' pierce or pass through the paraffine-wax or other preferred insulating material or substance susceptible of being melted at a 60 low temperature and with the wires again immersed in the mercury or other preferred conducting-liquid, or the paraffine-wax or other preferred insulating material may be melted and the wires readjusted as in the first 65 instance.

Having thus described the nature and objects of my invention, what I claim as new, and desire to secure by Letters Patent, is—

1. An electric cut-out device consisting of 70 two pieces of metal interposed in a circuit and engaging with and held by an insulated yoke and said pieces of metal embedded in an insulating substance susceptible of being melted and immersed in a conducting material in a vessel, and a band circumscribing 75 said vessel, substantially as and for the purposes set forth.

2. An electric cut-out device consisting of 80 two wires or pieces of metal interposed in an electric circuit and supported in or by a block composed of an insulating material, and said wires or pieces of metal in engagement with an insulated yoke and embedded in an insulating substance capable of being fused at 85 a low temperature and immersed in a conducting-fluid in a vessel surrounded by a band, substantially as and for the purposes set forth.

3. A cut-out device consisting of two pieces 90 of metal interposed in an electric circuit in engagement with a yoke, and said pieces of metal embedded in an insulating substance capable of being melted at a lower temperature than will melt said pieces of metal, and 95 portions thereof immersed in a conducting-fluid in a vessel, and means to prevent said vessel from falling and to allow of the device being readjusted after the circuit is broken, substantially as described.

4. The combination, with two pieces of metal interposed in a circuit and a supporting insulated yoke, of an insulating substance and a fluid contained within a vessel, and a supporting-yoke, substantially as and for the 105 purposes set forth.

In witness whereof I have hereunto set my signature in the presence of two subscribing witnesses.

STANLEY C. C. CURRIE.
